UNITED STATES PATENT OFFICE.

JULIUS PEGEL, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 13,678, dated February 27, 1883.

Application filed January 25, 1883. Term of patent 3½ years.

To all whom it may concern:

Be it known that I, JULIUS PEGEL, of New York city, in the county of Westchester and State of New York, have invented a new and 5 original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground *a* is a plain ground. The ground *b* conceals the ground *a* over the greater part 15 of the design, and is a plain ground ornamented in parts by various elaborate fret-like and border-like figures and geometric work. Over these grounds are disposed the flower groups A, B, C, and D. A is a large group of flowers 20 and leaves having a cluster of long flag-like leaves above. It rests upon the ground *b*, but throws some of its sprays downward into the ground *a*. B is a large flower and leaf group, resting chiefly on the ground *b*, but throwing 25 its blossom and leaf sprays far up into the ground *a*. C (shown in part at the left center and in part at the right upper and lower corners of the photograph) is a large flower and leaf group having flag-like leaves above, 30 and resting chiefly on the ground *b*, while projecting its sprays upward into a portion of the ground *a*. D (shown in part at the right center and in part at the left upper and lower corners of the photograph) is a smaller flower 35 and leaf cluster, and rests entirely on the ground *b*.

The ground *a* may be entirely omitted and its place filled by the continuation of the ornamented portions of the ground *b*.

I do not confine myself to the use of the 40 ground *a* in the design.

I claim—

1. The design for a ground for a carpet, consisting of the ground *b*, substantially as shown and described.

2. The design for a ground for a carpet, consisting of the grounds *a* and *b*, substantially as 45 shown and described.

3. The design for a carpet, consisting of the group A, substantially as shown and described. 50

4. The design for a carpet, consisting of the group B, substantially as shown and described.

5. The design for a carpet, consisting of the group C, substantially as shown and described.

6. The design for a carpet, consisting of the 55 group D, substantially as shown and described.

7. The design for a carpet, consisting of the groups A, B, C, and D, substantially as shown and described.

8. The design for a carpet, consisting of the 60 groups A, B, C, and D and the ground *b*, substantially as shown and described.

9. The design for a carpet, consisting of the groups A, B, C, and D and the grounds *a* and *b*, substantially as shown and described.

JULIUS PEGEL.
